UNITED STATES PATENT OFFICE

THOMAS E. FLOWERS, OF MEMPHIS, TENNESSEE

MAGAZINE GUN

Application filed December 14, 1929. Serial No. 414,054.

This invention relates to improvements in magazine firearms of the repeating, self loading, and automatic types, and more particularly to that type of self loading or semi-automatic rifle which uses a portion of the gases generated by the explosion of a cartridge to operate the mechanism, and that is adapted to be carried by the user and fired from the shoulder.

10 Rifles of the self loading and automatic types, and particularly those using the most powerful ammunition, have heretofore had numerous faults and disadvantages. To enumerate a few of these we have:

15 First, excessive length and bulkiness in the receiver, making the rifle heavy, and clumsy to handle;

Second, large expensive magazines, which are detachable and therefore subject to loss;

20 Third, breech mechanisms which compel heavy masses of metal to change their motions abruptly when the rifle is firing, leading to severe impacts between these heavy parts and their carriages or frames, and consequently causing rapid depreciation in many cases; and

25 Fourth, magazines which fail to align the axis of the cartridge with that of the barrel before and during the insertion of the cartridge into the firing chamber, leading in some cases to the mutilation of the cartridge and destroying accuracy.

The principal objects of my invention are:

(a) To provide an improved magazine rifle of the repeating or self loading type, capable of using special cartridges, in which the bullets are pre-rifled and hardened, (and consequently must be accurately fitted into the rifled portion of the barrel before the cartridge is fired), while retaining the ability to use the usual type of cartridge;

(b) To provide an improved magazine rifle of the repeating or self loading type, which is compact, contains an integral or non-detachable magazine, is durable under hard and continuous use, and which aligns its cartridges accurately with the bore of the barrel before and during the insertion of the cartridge into the firing chamber;

(c) To provide an improved magazine

rifle of the repeating or self loading type, which has a very strong, rigid, and powerful breech block, enabling the rifle to use cartridges of higher intensity than have heretofore been used;

(d) To provide an improved magazine rifle of the repeating or self loading type that is capable of delivering its bullets with greater accuracy, greater velocity, and much greater penetrating power into hard and tough materials than has heretofore been possible;

Further objects of my invention are:

(e) To provide a simplified and improved means for controlling pressures in the gas cylinder of the rifle;

(f) To provide an improved cartridge feeding mechanism, capable of positive and accurate handling of the cartridges, and especially adapted to handle the improved cartridges referred to above;

(g) To provide a link mechanism that loads cartridges into and extracts them from the firing chamber with a smooth, positive, and powerful action, and that also ejects cartridges or spent shells from the rifle by a new and improved method;

(h) To provide an improved and simplified firing mechanism that functions in an absolutely positive manner; and

(i) To provide an improved and strengthened means for actuating the above mentioned parts and mechanisms in the proper relation to each other, and in a smooth, positive and powerful manner.

Additional objects are:

(j) To provide a breech block that opens and closes the firing chamber with a substantially vertical motion, and does not move rearwardly, except through a slight inclination of the guiding grooves in the receiver in which the locking shoulders of the breech block fit;

(k) To provide a breech block which is longer than the cartridge used in the rifle, and which is hollowed out, or slotted, in a vertical plane through its central portion, this vertical well or slot allowing the cartridges to pass right through the breech block when coming into or out of the magazine and also

55

60

65

70

75

80

85

90

95

100

allowing the breech block to pass around the upper portion of the magazine when said breech block is depressed;

(l) To provide a breech block which carries a firing pin, or striker which is made very wide, and is slotted in the same manner as the breech block, for the same reason;

(m) To provide a vertical magazine of the single column type and being an integral part of the assembled rifle (i. e. it is not detachable) that receive its cartridges from a clip of several, or if desired singly, through the top of the receiver and breech block;

(n) To provide a magazine which has projecting flanges on its inner rear surfaces that fit into the extractor grooves of the cartridges, and, if these grooves are diametrically placed flat instead of circular grooves, prevent the cartridges from turning axially. This novel feature, which does not interfere in the least with the use of the ordinary cartridge, allows the use of a special cartridge, using a hardened, pre-rifled bullet, instead of the usual type;

(o) To provide a magazine which has a cartridge feeding mechanism, comprising a movable floor or lift, and means for raising and lowering this lift, so that it always moves in an accurate, predetermined manner;

(p) To provide an extracting and loading slide, having a head rotatably mounted on its forward end, which head is held and guided by flanges projecting upwardly from the main body of the breech block. This slide partakes of the vertical movement of the breech block, sliding away from the cartridge head when the breech block moves up to close the firing chamber, and sliding on to and gripping the cartridge head by its extractor grooves when the breech block moves down to open said firing chamber;

(q) To provide an extracting and loading slide, which has a movement independent of the breech block, in a backward and forward direction, which motion is controlled by link-work placed back of the breech block and fastened to the frame of the rifle;

(r) To provide link-work for such a slide that accomplishes a cycle comprising rearward extracting and forward loading movement of the slide, which rearward movement is timed to begin at the moment that the breech block is completely depressed, and which forward movement is timed to end at the moment the breech block begins to be elevated;

(s) To provide opposed extractor jaws on the head of this slide, which jaws are machined from one piece of metal, and are rigid, and which firmly grip the extractor grooves on the cartridge head, insuring positive loading and extraction of any cartridge, and allowing the special cartridge with pre-rifled, hardened bullet, to be loaded in such a manner that said bullet will be fitted accurately

a short distance into the rifled portion of the barrel;

(t) To provide action bars, reciprocally mounted in the frame and receiver of the rifle, and that pass on both sides of the magazine which actuate the cartridge feeding mechanism, link-work, and breech block with their associated parts, when said action bars are reciprocated;

(u) And in general, to provide the particular arrangement and combination of parts hereinafter further described and pointed out in the claims.

The means by which the foregoing and other objects are accomplished and the manner of their accomplishment will readily be understood from the following specification on reference to the accompanying drawings, in which:

Fig. 1 is a sectional elevation taken on the longitudinal center line of my improved magazine rifle showing the magazine and operating parts and fragmentary portions of the stock and barrel, and showing the working parts as they would appear when a clip of cartridges is ready to be inserted into the magazine.

Figs. 2, 3, and 4 are fragmentary views on an enlarged scale, showing particularly details of the magazine lift ratchet and intimately associated parts. Fig. 2 being a sectional plan taken as on the line II—II of Fig. 3, which corresponds to the line II—II of Fig. 1, with the striker spring case removed. Fig. 3 is a sectional elevation taken as on the line III—III of Fig. 2, and Fig. 4 is a sectional plan taken on the line IV—IV of Fig. 3.

Figs. 5 and 6 are vertical sectional elevations on the longitudinal center line of the rifle showing the breech mechanism with fragmentary portions of the stock and barrel, with the clip of cartridges in the rifle, one of the cartridges being in the barrel ready for firing, and Fig. 6 showing the remainder of the barrel with the gas operated mechanism and associated parts.

Figs. 7 to 12 inclusive are transverse sections on an enlarged scale taken respectively on the lines VII—VII, VIII—VIII, IX—IX, X—X, XI—XI, and XII—XII of Figs. 5 and 6, looking in the direction of the arrows.

Fig. 10A is a section taken on the line XA—XA of Figure 28, which is identically positioned with the line X—X of Figure 5, the view however showing a different position of the cartridges in the rifle, and particularly illustrating the action of the gripping fingers which temporarily retain a fired cartridge shell against ejection.

Figs. 13, and 14 are elevations from opposite sides showing fingers which grip and hold the empty shells just prior to ejection.

Fig. 15 is a section similar to Figures 1 and 5, showing positioning of certain of the parts

80

85

90

95

100

105

110

115

120

125

130

after a cartridge has been fired, and at the time when removal of the cartridge case from the firing chamber is about to begin.

Fig. 16 is an enlarged fragmentary detail, 6 showing the magazine lift lever ratchets and fragmentary portions of the magazine cover and lift lever, and parts intimately associated with the ratchets.

Fig. 17 is a transverse section on the 10 line XVII—XVII of Fig. 16, and Fig. 18, a similar transverse section on the line XVIII—XVIII of the same figure, both looking in the direction of the arrows.

Fig. 19 is a perspective view of the 15 secondary or auxiliary ratchet pawl, which takes the place of the principal magazine lift lever ratchet pawl when the rifle is operated by hand.

Fig. 20 is an enlarged side view of the pawl 20 case pin.

Fig. 21 is a sectional elevation showing the fired cartridge being withdrawn from the barrel by the link mechanism and associated parts:

25 Figs. 22 to 27, inclusive, are enlarged views of the breech block; Fig. 23 being a plan; Fig. 24 an end elevation of the right hand end; Fig. 25, an end elevation of the left hand end, and Figs. 26 and 27, transverse sections on the lines XXVI—XXVI and XXVII—XXVII respectively of Fig. 22, which is a side elevation.

Fig. 28 is again a sectional elevation on the longitudinal center line of the rifle, showing completed retraction of the fired cartridge, and elevation of a second cartridge into place for insertion into the barrel.

30 Figs. 29 to 35 inclusive are detail views of the action bars; Fig. 29 being a plan view of the two bars; Fig. 30 a side elevation of one of the bars; and Fig. 31 an inverted side elevation of the other bar, both views looking outward from the longitudinal center line.

45 Fig. 32 is an end elevation of the two bars.

Fig. 33 is a fragmentary sectional plan, taken on the line XXXIII—XXXIII of Fig. 30; and Figs. 34 and 35 are transverse sections on the lines XXXIV—XXXIV, and 50 XXXV—XXXV of Figs. 29 to 31 inclusive.

55 Figs. 36 and 37 are sectional elevations on the longitudinal center line of the rifle, with all the working parts except the action bar and sections of the pins engaged with it removed, a portion of the frame being also removed to give a clearer view of these parts, and being thus shown in order to more clearly show the way in which this bar acts. The action bar in Fig. 36 is shown in its extreme 60 forward position, and in Fig. 37 in its extreme retracted position. The other action bar, not shown in these figures, has an identical action with the one shown, except for a few minor details.

65 Fig. 38 is again a sectional elevation of the

gun, showing a cartridge being forced forward into the barrel and the shell of the previously fired cartridge being ejected from the receiver.

Figs. 39 and 40 are respectively an elevation 70 and plan of the striker.

Figs. 41 to 44 inclusive are views of the loading and extracting slide with its extractor head removed; Fig. 41 being a side elevation; Fig. 42 a plan; and Figs. 43 and 44, end 75 elevations thereof.

Fig. 45 is a bracketed view showing a center elevation and section, and two end elevations of the rear breech block pin with its 80 associated parts.

Figs. 46 to 49, inclusive, are views of the striker cam; Fig. 46 being a side elevation; Fig. 47 an end elevation; and Figs. 48 and 49, sections taken on the lines XLVIII—XLVIII and XLIX—XLIX respectively. 85

Figs. 50 to 53 inclusive are views of the extractor head; Fig. 50 being a side elevation; Fig. 51 a plan; Fig. 52 an end elevation of the right hand end; and Fig. 53 a similar end elevation of the left hand end of the 90 part.

Fig. 54 is a sectional elevation on the longitudinal center line of the gun, showing modified forms of the link mechanism and magazine, with their associated parts. 95

Fig. 55 is a fragmentary sectional plan on an enlarged scale, taken as on the line LV of Fig. 54.

Figs. 56, 57 and 58 are respectively views of a modified form of loading and extracting 100 slide with integral extractor jaws; Fig. 56 being a plan; Fig. 57 a side elevation; and Fig. 58 an end elevation thereof.

Referring now to the drawings in which the various parts are designated by numerals:

1 is the gun stock, which may be of any usual or approved design and which is attached to a receiver 2, as by a bolt 3. This receiver 2, comprises the transverse part at the rear end designated by that numeral, an inverted channel or U shaped portion having vertically disposed sides 2B and a curved bridge or top 2C connecting them, which portion extends forward to the previously mentioned forward end thereof. A frame 4, is attached to the receiver 2, and lies generally therewithin as by a bolt 5 at the rear end and by a transverse through bolt 6 at the forward end 2A. The forward end 2A of the receiver is internally threaded to receive a complementary thread on the rear end of the gun barrel 7. 8 is a take up nut and 9 a lock therefor. 10 is the rifling in the barrel. 110

115 Disposed below the barrel 7 is a gas cylinder 11, which is secured to the barrel by sleeves 12 and 13 (Fig. 6). 14 and 15 are screws which pass transversely through these sleeves respectively and which engage suitable notches in the barrel to prevent longi- 120

125

tudinal and rotative movement of the sleeves with reference to the barrel. The gas cylinder also is notched to receive the screw 14 to prevent rotative movement of the cylinder in the sleeve. The cylinder at its forward end is threaded into the sleeve 13 and is thereby held against longitudinal displacement. 16 is a gas passage or port from the barrel through the sleeve 13 into the cylinder.

10 The forward end of the cylinder is internally threaded to receive an externally threaded plug 17 which is shown screwed in to its fullest extent. The inner portion of this plug 18 is cylindrical and closely fits the bore of the gas cylinder. When screwed in as shown this cylindrical portion closes the gas port 16, and when retracted opens up and regulates the amount of opening from this port into the gas cylinder. Preferably the 15 plug is provided with a drill 19 which may be used to clear the port 16 of any obstruction. An opening 20 preferably threaded is provided in alignment with the port through which the drill may be inserted into the port. 20 If desired, an enlarged shank 21 on the drill may be similarly threaded, so that the drill 25 may be forcibly inserted in the port.

Disposed in the cylinder 11, is a plunger 22, which has an extension 23 of reduced size 20 extending rearwardly therefrom beyond the rear end of the cylinder. The cylinder 11 is provided at the rear end with a head 24 which is bored out to form a guide for the plunger extension and which also serves as 25 an abutment for a short and heavy buffer spring 25. 26 is a washer disposed against this spring which washer serves as an abutment for a long compression spring 27, against which the plunger 22 abuts and acts. 30 28 is a gas release vent. 29 is a collar clamped on the plunger extension to limit return movement. The plunger extension beyond this collar is grooved circumferentially to form an annular shoulder 30 at its 35 end. This shoulder engages oppositely disposed bars 31, 32 hereinafter designated as action bars. Depending from these bars are spurs 31A, 32A. (See Figs. 30, 31 and 32.)

Disposed in the lower portion of the sleeve 50 12 is a transverse pin 33 on which a forearm frame 34 pivots. This frame swings downward about the pin 33 as a hinge and uncovers the forward ends of the action bars and the rear ends of the gas cylinder. When 55 swung down it also releases the barrel and permits unscrewing the same from the receiver.

The action bars 31, 32 are horizontally disposed and extend rearwardly from the plunger extension 23. They are slidably mounted in rectangular grooves formed in part in the frame 4 and in part in the sides 2B of the receiver. These grooves are designated in Figs. 7 and 8, and Fig. 36 by the numeral 35. 60 They terminate substantially against the rear

end of the frame 4. Action bar 31 is shown in Fig. 36, in its extreme forward position and in Fig. 37 in its extreme rearward position. Bar 32 has an identical movement.

Disposed within the receiver and frame and lying between the action bars 31, 32, is a magazine comprising oppositely disposed walls 37, 38, which extend from above the action bars 31 downward below the bottom of the frame. 39 is a magazine cover which forms the closure for the bottom of the magazine. This cover is hingedly pivoted at its forward end on the transverse bolt 6 and at its rear end is pivotally connected by a pin 40 to a finger lever 41. This lever is forked 70 to embrace the rear end of the magazine cover 39 and the magazine walls 37, 38, the ends 41A of the fork being rounded, and is provided with outwardly projecting bosses 42 which engage oppositely disposed substantially horizontal grooves 43 in the frame 4. 75 44 are vertical ribs which project inward from the magazine walls and which are adapted to engage a groove 45 in the cartridge shell 46. (Fig. 38.)

Disposed in the magazine is a movable floor or cartridge lift 47 which is grooved on opposite sides to loosely engage the ribs 44 above mentioned. This lift is raised and lowered in a substantially horizontal position by a lift 80 lever 48 and a bell crank lever 49. The lever 48 carries a pin 50 which engages oppositely disposed slots 51 in the lift, and the lever 49 carries a boss 52 which engages a slot 53 in one side only of the lift. The levers 48 and 49 85 are pivotally connected by a sleeve 54 which preferably is an integral hollow boss projecting from one of the levers. The lever 48 projects forwardly beyond the sleeve 54, and is pivoted on the transverse bolt 6. The lever 49 is provided with an integral bell crank arm from which a pin shaped boss 55 projects laterally into an arcuate slot 55A in the magazine, the pin and slot coacting to determine the movement of the opposite end of the bell 90 crank lever as it is moved by the lift lever.

The mechanism by which the lift lever is operated, comprises a pawl case 56 which embraces the lift lever and is pivoted on the pin 6. This case is bored out to receive a pawl 57 which is urged rearwardly by a compression spring 58. The under side of the rear end of the pawl engages successively steps 59, cut on the forwardly projecting end of the lift lever. 60 is a transverse pin carried by the 100 pawl. This pin projects through slots 61 in the pawl case and extends beyond such case, so that it may be engaged by projecting cam surfaces 62 on the forward ends of the magazine cover 39, so that when the cover is thrown downward the cam surfaces force the pin 60 forward and disengage the pawl from the steps 59 to permit return, downward movement, of the cartridge lift. Mounted in the forward end of the pawl case 56 is a trans- 105

verse pin 63, preferably of the shape shown in Fig. 20. This pin extends laterally beyond the pawl case and is held against lateral movement by the spring 58, which spring abuts against the reduced diameter center portion of the pin. The projecting ends of the pin extend into slots 64 in the action bars 31, 32, so that rearward movement of the bars eventually on each stroke depresses the pin and with it the pawl case 56, thus causing the pawl to depress the forward end of the lift lever after engagement of the pawl and steps has been effected. Carried by the rear end of the pawl case and rotatably mounted therein is a pawl member 65, which passes through an arcuate slot 66 in the lift lever. The ends of this slot striking against this member limit the relative movement of the pawl case and the lift lever. 67 are ratchet teeth, with which the pawl member may be engaged. 68 is an arm on the pawl member, which engages a surface 69 on the magazine cover 39 to hold the pawl member and ratchet teeth out of engagement when the magazine cover is closed as during normal operation. A spiral spring 70 (Fig. 1) urges the pawl member into engagement with the ratchet teeth. When the magazine cover is swung downward the arm 68 can swing upward and a lug 71 on the arm can come into an undercut notch 72 on the action bar 31. Such movement permits the engagement of the pawl member and ratchet teeth.

Adjacent and rearward from the vertical ribs 44, the magazine is vertically drilled to receive a hollow cylindrical step member 73, substantially one quarter of which is cut away (Fig. 4). Steps 74 corresponding in number to the steps 59 are cut into one of the vertical edges thus formed. An integral latch 75 projects rearwardly from the cylindrical step member. The steps successively engage the rear of the cartridge lift 47 as this lift is raised step by step during firing of the gun.

Cartridges 46 are carried for insertion in the gun by a clip 76. This clip is inserted in notches or grooves 77, Figs. 15 and 21, in the gun and pushed downward therein to position shown in Fig. 1.

78 is a loading and extracting slide having arcuate sides and which is reciprocably mounted in guideways 79 of complementary cross section which are formed in a breech block 80. Projecting axially from the forward end of this slide is a shank 81, having an enlarged collar or head 82 thereon. Engaging over this head and rotatable about the longitudinal axis of the slide is an extractor head 83 having ribs which engage the extracting grooves of the cartridges. Extending laterally from this head are lugs 84 which engage in grooves 85 cut in the guideways of the breech block whereby reciprocating motion of the slide may be effected and in addi-

tion rotative motion be imparted to the head.

86 is a transverse pin extending laterally beyond the slide 78 on the ends of which pin, the forked end of a connecting link 87 is hinged. The link 87 extends rearwardly and is hinged by a pin 88 to a small link 89. The pin 88 extends laterally beyond the link 87 into grooves or slots 90 in the sides of the frame 4. The small link 89 is connected by a pin 91 to a slotted link 92, which in turn is pivotally connected by a pivot pin 93 to the frame 4. Disposed in the slot of the link 92 is an action pin 94 which extends through action pin slots 95 in the frame and has its ends disposed in the end slots of the action bars 31—32. Depending below the link 87 is a lug 87A which, when the link is in forward position as shown in Fig. 5, prevents accidental displacements such as might occur if the gun was inverted, of the cartridge 46 from the magazine.

96 is a striker, which carries at its forward end the usual firing point 97. The central portion 98 of this striker is cut away to permit passage of the magazine and the cartridges therethrough. Extending downward at the rear end of the striker are flanges 99 and 100 having similarly inclined rear and forward edges respectively, which define an inclined slot 101. The striker is slidably mounted in horizontal slots 102 in the breech block.

The breech block 80 comprises essentially two longitudinal bars 103 disposed parallel to each other and spaced apart to embrace the magazine before mentioned. At the rear end a bridge 104 holds these bars properly spaced. At the forward end a bridge 105 serves a similar purpose and in addition forms an abutment for the cartridge when fired. Shoulders 105A cooperate with the rear walls 105B of grooves in the side walls of the receiver to take up end thrust of the breech block during firing and also serving to guide vertical movement of the breech block. Through the abutment 105 is a central hole 106 which permits passage of the firing point 97 to the cartridge primer. Extending downward from the bars 103 at the forward end are lugs 107 and at the rear end lugs 108, in which holes 109, 110 respectively are provided to receive pins 111, 112 which extend laterally, the first into grooves 113 in the action bars and the second into grooves 114, 115 in the bars 31, 32 respectively. Longitudinal movement of the action bars acting through these pins lowers and raises the ends of the breech block synchronously.

116 is a cam block for actuating the striker 96. This block is vertically movable, being guided by projecting ears 117, at its upper end, which ears engage in grooves 118 in the lugs 108 at the rear ends of the breech block 80. 119 is an inclined cam cut in the upper end of the cam block which cam engages the

inclined walls of the slot 101, between the striker flanges 99, 100, and changes vertical movement of the cam block into horizontal movement of the striker. 120 is a lug extending from the rear side of the cam block near the lower end thereof, which lug is engaged by a sear 121 to hold the cam block down, i. e., in cocked position. The lower position of the lug has a central rib 122 which is flanged by two undercut or inclined sides 123. The sear is forked to allow passage of this rib so that on downward movement of the cam block the inclined surfaces of the sear will be engaged by the inclined sides 123 of the block to retract the sear. 124 is a spring urging the sear toward the cam block. 125 is the pin on which the sear is pivoted. 126 is a latch which is pivoted to the sear, on a pin 127, at a point below the pin 125. This latch is engaged by the rib 122 as the cam block descends and is thereby swung forward to disengage the latch (126) from the underside of a lug 128 on a trigger 129. The upper portion of the latch 126, has an arcuate groove 130 cut therein, which limits its forward and rearward movement by impingement on the sear pin.

The trigger 129 is mounted in an extension from the rear end of the magazine on a pin 131 and bushing. The forward end is urged upward by the spring 124 and such upward movement is limited by a transverse plate 132 forming part of the extension in which the trigger is pivoted.

The center of the cam block is vertically slotted so that the pin 112 may pass therethrough. The lower end 133 of this slot is inclined transversely and the pin 112 carries a beveled lug 134, similarly inclined, which cooperate when the cam block is raised. The pin 112 comprises portions of different diameters. The end of the larger portion being beveled. On the smaller portion is the beveled lug 134 and a sleeve 135, preferably of the same outer diameter as the larger portion of the pin, the outer end of this sleeve also being beveled. This pin as before stated is disposed in the grooves 114, 115, of the action bars. The rear end of the groove 114 is inclined inwardly i. e. the groove becomes very shallow and the groove 115 is correspondingly inclined outward, so that as the action bars begin a backward movement, the pin is moved sharply to one side and the cam block is correspondingly forced downward.

The cam block 116 is actuated by a compression spring 136. This spring bears against the lower end of the cam block and is centered and guided by a pin 137 extending downward from the block. The lower end of the spring is housed in a spring case 138, which is square outside and cylindrically bored. This case is slidably disposed in vertical slots 139 in opposite walls of the magazine 37-38. Depending below the spring

case is an integral cam 140, which projects downward into a longitudinal groove 141 in a slidable member 142. This member is mounted for longitudinal movement in grooves 143 in the magazine side walls. The member 142 is transversely grooved to receive a roller 144 which rests on the bottom of the grooves 143. 145 is a smaller and shorter roller disposed transversely across the slot 141 which roller rests directly on the top of the roller 144, and is held in such position by suitable vertical slots in the member 142 adjacent the longitudinal groove therein. Longitudinal movement of the member 142 is effected by the pin 40 coacting with the inclined walls of a slot 146 in the member 142. The pin 40 is of less diameter than the slot width, so that it moves the member forward or backward as the case may be, until the roller 145 passes the point of the cam 140 after which the downward thrust of the spring 136 will complete the movement in either case.

147 is a lug projecting downward from the step member 73 into an arcuate slot 148 in the member 142. The movement above mentioned of the member 142 effects a limited turning movement of the step member.

149 is a notch (see Fig. 31) in the lower inside edge of the action bar 32 with which the latch 75 engages when turned to the dotted position 75A of Fig. 4.

150 are oppositely disposed fingers having pivot pins 151 in the receiver side walls. The lower ends 153 of these fingers extend below the pivot pins 151. 154 are grooves in the action bars 31 and 32 into which the finger ends 153 may swing when the action bars are forward, thus spreading the fingers apart but which slots terminate in such position that when the action bars are retracted, solid portions of the bars are presented to lock the fingers in closed position. In Fig. 10 the fingers are shown spread apart, in Fig. 10A they are shown locked. 155 are springs which act to hold the fingers in closed position. Preferably, the fingers are made in two parts as shown in Figs. 13 and 14. The secondary part 150A is disposed toward the rear end of the gun and is provided with a rib 156 which engages the cartridge grooves when cartridges are ejected and also when they are inserted by hand.

157 are inwardly disposed projections from the receiver walls which define a slot of sufficient width to permit passage of the reduced forward end of the cartridge shell, but will not permit passage of the body of the shell whereby single cartridges are prevented from being placed improperly in the gun.

158 is a spring actuated plunger, mounted centrally in the sleeve 54 of the bell crank lever 49.

The operation of the rifle is as follows: Starting with the magazine and firing chamber empty, the striker forward, the mag-

azine lift raised to the position shown in Fig. 1, and the finger lever closed, the parts will be seen substantially as shown in Fig. 5, except that in this view the striker is retracted, the magazine and firing chamber are loaded, and the cartridge lift is depressed.

The finger lever 41, is pushed downward and forward manually, this action being continued until the lever reaches the position shown in Fig. 1. The actions that take place during this movement in their proper sequence are as follows:

The first opening movement of the finger lever causes the pivot pin 40, which joins the finger lever 41 to the magazine cover 39 to press forward the cam member 142, thereby turning the step member 73, out of engagement with the cartridge lift 47. This forced movement of the cam member 142 continues until the upper roller 145, of the two anti-friction rollers 145, 144, has passed considerably by the central part of the V-shaped cam 140 on the bottom of the striker spring case 138. Through the downward action of the striker spring 136 on this case, and the action of the V-shaped cam on the upper roller, the cam member will now move forward independently of the pivot pin 40, still further turning the step member 73 and bringing the locking edge of the latch 75, which is an integral part of the step member, into contact with the inner side of the action bar 32, and into position on further movement of the action bar to engage a notch therein.

As the finger lever continues its opening movement the arcuate surfaces 41A on the forked end of this member, begin to move rearwardly, forcing back the action bars 31, 32 by pressing against the spurs 31A, 32A, that project downward therefrom. The forked end of the finger lever has outwardly projecting bosses 42 which engage the grooves 43 in the frame 4, thereby guiding these portions of the finger lever, when in motion, in a substantially horizontal direction.

The magazine cover 39 swings downward about the transverse bolt 6, during the greater part of the opening movement of the finger lever, causing the cam surfaces 62 on the forward ends of the magazine cover to force the transverse pin 60 forward. The pin 60 carries with it the pawl 57, disengaging the pawl from the steps 59 on the lift lever 48. The opening movement of the magazine cover also releases the arm 68 of the pawl member 65, allowing the spiral spring 70 to press the lug 71 on said arm against the under surface of the action bar 31.

When the finger lever reaches the position shown in Fig. 1, the cartridge lift 47 will be unlocked from the step member 73, the lift lever 48 will be disengaged from the pawl 57, and the pawl member 65 will still be disengaged from the ratchet teeth in the arcuate slot 66. The cartridge lift and its actuating

mechanism will therefore be free to move downward to allow loading of the magazine. Accidental motion of the cartridge lift and associated parts is prevented by the frictional holding action of a spring actuated plunger 158, the rounded end of which sets preferably into an arcuate series of holes of smaller diameter than this plunger, in the magazine side wall 38.

The finger lever during this opening movement forces back the action bars; these in turn depress the breech block 80 and its associated parts, and operate the link mechanism, which withdraws the loading and extracting slide 78 with its associated parts, rearwardly from the firing chamber. (These and other actions will be more fully set forth in the description of the operation of the rifle during semi-automatic firing.) When the loading and extracting slide has completed its rearward motion, the latch 75 of the step member 73 drops into the notch 149 cut in the lower inner surface of the action bar 32, and prevents the compression spring 27 from returning the action bars to their closed position before desired.

The parts are now in position for loading the magazine, the cartridges being inserted through the opening in the top of the receiver, either singly or in clips of 6 or less, as shown in Fig. 1. If clips are used, the clip is first inserted for a short distance into the clip guiding grooves 77 of the receiver and is brought to a stop by impinging on the upper side of the extractor head 83. The clip on being inserted forces the locking and guiding fingers 150 and 150A, out of the way. When the clip has been fully inserted, the cartridges are stripped from the clip by pressure on the upper cartridge, forcing the cartridges to slide past the cartridge gripping jaws on the extractor head 83 into the grip of the similar jaws or ribs 44, on the magazine sidewalls 37, 38, except for the last or upper cartridge, which is left in the grip of the jaws on the extractor head.

If the cartridges are loaded singly, each cartridge is placed with its groove (or grooves) in position to be engaged by the guiding ribs of the secondary fingers 150A, and pressed downward therein by the user. In being pressed into the receiver the cartridge will force aside the locking fingers 150 but as these members can move independently of the fingers 150A such single cartridges will always be gripped and guided by the latter. If desired, each cartridge may be pressed past these fingers into the extractor head jaws, but it will be found more convenient to load all except the last cartridge in the manner first described, pushing the top or last cartridge only, completely off of the guiding fingers and into the grip of the extractor jaws.

The magazine having been loaded, the fin-

ger lever is closed, which action first allows the pawl 57 to be pressed rearwardly by its spring into contact with the stepped portion of the lift lever 48, and just before complete closure forces back the member 142, which turns the member 73 and its latch 75 out of engagement with the action bar 32, and into position for one step of said step member to engage the lower rear edge of the cartridge 10 lift.

The compression spring 27 will now force the piston or plunger 22 forward, which carries with it the action bars 31, 32. The action bars force the link mechanism to reverse its 15 opening action and push the loading and extracting slide with its extractor head and loaded cartridge forward, until the cartridge is inserted in the firing chamber. The link 87 ejects the empty clip from the rifle during 20 this action. During the forward or loading movement of the extractor head and its associated parts, the frusto-conical bosses 84 of this extractor head which project into partly helical grooves cut into the guideways 25 79 of the breech block, cause the extractor head to first turn through a small angle in the opposite direction to the twist of the rifling of the gun barrel, and just before the completion 30 of the forward motion, to turn through the same angle, in the same direction, and with the same twist as the rifling of the gun barrel. The helical portions of the grooves in the guideways are preferably separated by a straight portion of considerable length, as 35 shown in Fig. 1.

The purpose of this construction is to allow this rifle to use a special cartridge which has hardened and pregrooved or rifled bullets, this grooving or rifling being complementary to that in the gun barrel. The 40 shells of these cartridges grip the lands or grooves of the bullets, always holding them in a definite position as regards axial rotation in relation to diametrically opposed flat 45 grooves formed adjacent to the rear end or head of the cartridge shell, these flat grooves taking the place of the usual circular extractor groove. As the rifling in the barrel is made so as to have a definite relation as to 50 rotative position in relation to the extractor jaws, and the extractor jaws grip the flat grooves in the cartridge heads and prevent the cartridges from having rotary motion in relation to said jaws, the bullets can be made 55 to enter the rifling accurately, and be perfectly fitted for a short distance into said rifled portion of the barrel. It will be seen that this construction in no wise interferes with the use of the ordinary cartridges in 60 this rifle.

The loading of the cartridge into the firing chamber being substantially completed, the forward motion of the action bars and their associated parts continues until the breech 65 block has been raised into locked position.

This last movement lifts the jaws of the extractor head out of engagement with the grooves in the cartridge shell and substitutes similar jaws cut on the breech block in their place. The cam block 116 is held in cocked 70 position by the sear 121, the beveled lug 134 is pushed back out of the way of said cam block, and the striker 96 is forced back and brought upward with the breech block into firing position. 75

The parts will now be in the position shown in Figs. 5 and 6, these views showing the rifle ready for firing.

If the user desires to unload the rifle without firing, the finger lever is operated as before, except that instead of stopping the opening movement of this part in the position shown in Fig. 1, it is continued until the action bars have been fully retracted. When the action bars are forced rearward 85 past the position shown in Fig. 1, the undercut notch 72 in the action bar 31, allows the spiral spring 70 to swing the lug on the arm of the pawl member 65 upward bringing the pawl member into engagement with one of 90 the ratchet teeth 67. The continued rearward motion of the action bars now actuates the cartridge feeding mechanism, forcing the loaded cartridge in the grip of the extractor jaws upward onto the guiding ribs of the 95 fingers 150A, and pushing the cartridge immediately below into the extractor jaws. The user now closes the finger lever, allowing the compression spring 27 to close the action in the usual manner, during which movement the upper cartridge will be ejected from the rifle and the one in the grip of the extractor jaws be loaded into the barrel. This action is then repeated until the rifle is completely unloaded. 100

Returning to the rifle as shown in Figs. 5 and 6, the semi-automatic functioning is as follows:

First, the trigger 129 is pulled by the user, forcing down the sear latch 126, and turning the sear 121 about the sear pin 125, releasing the cam block 116, which is forced upward by the compression spring 136. The striker 96 is thrown forward by the cam block 116, firing the cartridge 46. 110

As soon as the bullet passes the port 16, near the muzzle of the rifle, gas under high pressure passes through said port into the cylinder 11, forcing back the piston 22, and action bars 31, 32 attached thereto. As the 120 piston is forced back, it compresses the piston spring 27. As the piston passes the port 28 the gas pressure is released, allowing the momentum of the moving-parts to complete the opening movement. 125

The action bars moving rearwardly first force the rear breech block pin 112, for a short distance transversely, or in the direction of the pin's axis, causing the inclined surface of the lug 134, to depress the cam 130

block 116, which in turn draws back the striker until it is clear of the exploded cartridge. The curved grooves in the action bars then act on the protruding ends of the front and rear breech block pins 111, 112, depressing the breech block 80 and with it the striker 96, the cam block 116 and the loading and extracting slide 78, with its rotatable head 83, causing said head to slide its jaw into the groove or grooves in the head of the exploded cartridge.

During this downward movement of the breech block, the connecting link 87, which is pivotally connected to the loading and extracting slide 78, near its forward end, swings downward around the pin 88, as a pivot, causing a slight net motion to the rear, of the extractor head, the cartridge held by the extractor head, and the loading and extracting slide. This motion is extremely powerful, and will start even a tightly stuck cartridge shell so that its further extraction is made easy. To compensate for this slight rearward motion of the extractor head and its associated parts, the breech block does not move in a direction exactly at right angles to the barrel, but moves instead in guiding ways inclined slightly to the rear, said inclination being enough to cause the breech block to move backward from the breech during the downward movement of the breech block, the same distance as the net rearward motion of the extractor head and its associated parts. Just before the downward motion of the breech block is completed, the under surface of the rib 122 on the cam block engages the forward projecting portion of the latch 126, first swinging this latch out of engagement with the trigger 129. Immediately after the latch 126 has been disengaged from the trigger, its motion relative to the sear 121 is halted by impingement of the rear end of the arcuate groove 130 of said latch, on the sear pin 125. The sear and latch then acting as a solid member swing together through a small angle about the sear pin, until the catch on the sear has been forced into position to hold down the cam block.

The action bars 31, 32 carry with them in their motion, the action pin 94, which however is free to move a limited amount in a vertical direction in relation to these bars. This pin is held at both ends by vertical slots in the action bars. Starting at one end of the action pin 94, it passes through one action bar, through one side of the frame 4, through the slotted link 92, through the other side of the frame 4, and through the other action bar. In the frame are slots 95, 95, that direct the motion of the action in relation to the slotted link 92, and the action bars 31, 32. It will be seen that these slots are straight, through a distance necessary for the action bars to completely depress the breech block, and are directed radially toward the axis of the pin

on which the slotted link 92 turns. This construction prevents the action pin from causing any motion of the slotted link until the end of the straight portion of these slots has been reached by said action pin, the only effect of the action pin when in said straight slots being to lock the slotted link from turning.

As soon however as the action bars carry the action pin into the curved portions of the slots in the frame, the slotted link is forced to begin turning about the pin 93, this motion being transmitted through the small link 89, to the pin 88, and from the pin 88 to the connecting link 87. The connecting link in turn draws the loading and extracting slide, with the extractor head and exploded cartridge backward from the firing chamber.

The pin 88 which joins the small link 89 to the connecting link 87 and which projects at both its ends into the slots 90, in the frame, is forced by these guiding slots to move in a definite pre-determined manner, the shape of these slots being such that the angle between the direction of the force applied to this pin 88, by the small link 89, and the direction in which motion can take place never exceeds 48 degrees. Thus the linkage withdraws the empty shell from the firing chamber in a smooth and efficient manner.

When the empty shell has been withdrawn nearly to its rearmost position by the extracting and loading mechanism, this motion is rapidly but smoothly brought to a stop, the stop occurring when the jaws of the extractor head, the corresponding guiding flanges 44 on the rear interior surfaces of the magazine walls, and the guiding flanges on the two guiding fingers 150A, form one continuous pathway from the bottom of the magazine to the top of the receiver.

The two action bars, and the action pin 94 continue to move to the rear, though the link action has come to an end. This continued rearward motion brings the curved portions of the slots 64 in the forward end of each action bar against the transverse pin 63, in the forward end of the pawl case 56, forcing down this part and consequently forcing the magazine lift lever to raise the magazine lift through the space occupied by one cartridge. If the magazine happens to be completely filled at the beginning of this movement, the magazine lift lever is forced to move by action of the pawl member 65, on the upper end of the slot 66, but for all cartridges after the first, this motion is forced by the action of the pawl 57, on the steps 59 of the lift lever 48.

It will be seen that when the magazine lift is forced upward, the empty shell will be forced from the extractor head jaws by the loaded cartridge immediately below, this cartridge taking its place in the grip of the jaws of said extractor head, and the exploded

cartridge moving upward into the grip of the ribs of the guiding fingers 150A—150A. The exploded cartridge cannot move further upward when the action is in this position, being prevented by the curved horns of the two fingers 150—150, said fingers being locked during upward movement of the cartridge lift. The loaded cartridge is thus brought accurately into line with the bore of the rifle, and cannot move past this position.

As soon as this lifting action has been completed, the piston spring 27 which is now completely compressed acts like a solid member, bringing the remaining force of inertia left in the moving parts directly against the powerful buffer spring 25. This buffer spring brings the rearward motion of the action bars and associated parts to a rapid halt and immediately impels them in the opposite direction.

As the forward motion starts, the slots 64 in the forward portion of the action bars, push the front end of the pawl case 56, upward, causing the pawl to slide across the end of one of the steps of the lift lever, until it clicks backward into place on the top of said step.

The link action now comes into play in the reverse direction, forcing a loaded cartridge into the firing chamber and at the same time ejecting the empty shell through the top of the receiver by the action of the inclined upper surface of the connecting link 87 on the under rear end of said empty cartridge.

When the link movement is completed, the action bars force the breech block upward into locked position, removing the extractor head jaws from the cartridge and substituting the similar jaws of the breech block.

As the cam block is held in the depressed position, by the sear during this movement, and the striker moves upward with the breech block the striker is forced still further to the rear by the action of said cam block on the rear surface of the slot 101. This action takes place whether the trigger is held back or released, the trigger being entirely disengaged from the latch 126 as long as the breech block is fully depressed. The last closing movement of the action bars force the rear breech block pin 112 and associated parts to move axially for a short distance, or into the same position as before, keeping the beveled lug 134 from interfering with the motion of the cam block when the rifle is again fired.

In Figures 54 to 58, inclusive, I show modified forms of the cartridge feeding mechanism, the link mechanism, and the loading and extracting slide.

The forward portion of Fig. 54 shows a spring actuated cartridge feeding mechanism. The cartridge lift 160 remains as before, except that its top rear end has been partly cut away to allow a modified step member 161 to lock this cartridge lift against up-

ward movement. The modified step member 161 has its steps set in the opposite manner to the original step member, that is, it holds the lift down, whereas in the previous form it supported the lift, and is now turned into locked position by a torsion spring 162. This torsion spring is held in place by a screw 163. A slot 164 is cut through the cylindrical wall of the member 161 to accommodate a transverse pin 165, (Fig. 55) which is also mounted in the hole 166 through the magazine. One end of this pin rests against the rounded end 167 of the slot 164, the other end of the pin against the bottom of the groove 168, (shown dotted), in the action bar 31. The groove 168 is inclined inwardly, or made shallower near its forward end.

The lift lever 169 carries the bell crank lever as before, but the steps 59, arcuate slot 66, and ratchet teeth 67 are omitted. The spring plunger and spring are also omitted. The lift lever 169 is urged to raise the cartridge lift by a torsion spring 170, (shown dotted). This spring has one of its ends secured against the forward portion of the lift lever, it coils about the transverse bolt 6, and has its other end secured against the lower side of a lever arm 171. The lever arm 171 and the lift lever pivot about the bolt 6. The lever arm, which takes the place of the pawl case, carries the transverse pin 63 in its forward end as before, and has a projecting tooth 172 on its rear portion. The lift lever has a block 173 projecting transversely from its forward side, which acts as a stop for the tooth 172. The pin 63 engages slots 64 in the action bars as before.

When the rifle fires the action bars moving rearwardly, first lock the fingers 150 and 150A from moving, then the action bar 31 pushes the pin 165 inward, turning the step member 161 out of engagement with the cartridge lift, and allowing the torsion spring 170 to lift a cartridge into position for insertion into the firing chamber. On the return movement the torsion spring 162 turns the step member 161 back into position for engaging the cartridge lift, and in doing so pushes the pin 165 back into the deeper portion of the groove 168, after which the fingers 150—150A are unlocked. When the last cartridge in the rifle has been fired, the cartridge lift pushes the empty shell from the extractor jaws into the fingers 150A, and must be depressed out of the way of the extractor before the action can close and eject this shell. In this position the tooth 172 will be in contact with the block 173 and the lever arm and lift lever will act as a solid member. Therefore the forced upward motion of the lever arm as the action bars move forward, will turn the lift lever enough to remove the cartridge lift from in front of the extractor, before the extractor begins to move forward.

As the latch 75 is now omitted from the modified step member, a simple spring latch, (which is not shown) must be introduced to hold back the action bars in position for loading the magazine.

The rear portion of Fig. 54 shows a modified form of the link mechanism for actuating the loading and extracting slide. (The action bars are shown partly retracted in both portions of Fig. 54.)

The action bars 174—174A (a portion of 174 is shown dotted), differ from the action bars 31—32 in being longer, and having slots 175 that curve downward and forward from their rear upper ends until these curves become tangent to the direction taken by the action bars when in motion. The slots then become straight for the remainder of their length. The slotted link 176 has a slot 177 that extends longitudinally for a short distance near the pivot pin 93, and then curves slightly and again becomes straight for a longer distance. When the action is in closed position, this longer straight portion lies parallel with the direction taken by the action bars when in motion, as shown in Fig. 54. The frame 4 has slots 178 which are straight in their forward portions, and in their most forward portions, coincide in longitudinal and vertical position and direction with the longer straight portion of the slot 177 when the action is closed. Then extend straight rearwardly until approximately above the pivot pin 93 where they begin to curve downward, and continue to curve until substantially a quarter circle has been described. The centers of the rounded ends of these curved portions, coincide in vertical position with the centers of the straight portions of the slots 175 in the action bars.

The slotted link 176 is pivotally connected to two small links 179 which take the place of the small link 89, and serve the same purpose.

The action pin 94 passes transversely through all these slots. When the action bars move rearwardly, the pin is carried back until it reaches the ends of the slots in the frame, when it stops and allows the action bars to move further to the rear for a distance equal to the straight portions of the slots in these members. The action pin actuates the linkage from the position shown in Fig. 54, until it reaches the rear ends of the slots in the frame. When the action bars return, these actions are repeated in reverse order.

Figs. 56 to 58 inclusive show a modified form of loading and extracting slide; in which the extractor jaws are made integral. The slide in this case has longitudinal ribs 180, which take the place of the arcuate sides of the original slide 78 for guiding purposes.

The guideways in the breech block in this

case are made to fit the sectional shape of this modified slide.

The modified slide will not handle cartridges with bullets that must be fitted a considerable distance into the rifling of the gun barrel.

I claim:

1. In a gun having a rifled barrel, a reciprocatable slide, a head rotatably mounted on the forward end of said slide, said head having oppositely disposed jaws, ribs projecting inwardly from said jaws and adapted to engage the groove or grooves of a cartridge, oppositely disposed guides carrying said head, said guides having complementary grooves therein, and said head having lugs projecting therefrom into said grooves, said grooves each having their rear portion spiraled reversely to said rifling, a central longitudinal portion leading therefrom and a forward portion spiraled in conformity with said rifling.

2. In a gun having a rifled barrel, a reciprocatable slide, a head rotatably mounted on the forward end of said slide, said head having oppositely disposed jaws, ribs projecting inwardly from said jaws and adapted to engage the groove or grooves of a cartridge; oppositely disposed guides carrying said head, said guides having complementary grooves therein and said head having lugs projecting therefrom into said grooves, said grooves each having their rear portion spiraled reversely to said rifling, and the forward portion spiraled in conformity with said rifling.

3. In a gun, a receiver, a breech block vertically slidable in said receiver, said breech block having longitudinal guideways therein, means for aligning the axis of said guideways with the barrel of said gun, a cartridge engaging head reciprocatably mounted in said guideways and means for reciprocating said head to place or remove a cartridge from said barrel.

4. In a gun having a rifled barrel, a receiver, a breech block vertically reciprocatable in said receiver, said breech block having a longitudinal bore, means for aligning said bore with the barrel of said gun, a cartridge engaging head reciprocatably mounted in said bore, means for reciprocating said head to place or remove a cartridge from said barrel, and means for imparting a rotary motion to said head during such reciprocation.

5. In a gun, having a rifled barrel, a receiver, a breech block mounted therein, said breech block having a longitudinal bore and grooves extending into the walls of said bore, said grooves, each having its rear portion spiraled reversely to said rifling, a longitudinally disposed central portion and a forward portion spiraled to conform to said rifling, a cartridge receiving head recipro-

- catably mounted in said bore, lugs extending from said head into said grooves, and means for advancing said head, to place a cartridge in said barrel, and retracting said head to remove a cartridge from said barrel.
- 5 6. In a gun, having a rifled barrel, a receiver, a breech block mounted therein, said breech block having a longitudinal bore and grooves extending into the walls of said bore, said grooves each having its rear portion spiraled reversely to said rifling, and its forward portion spiraled to conform to said rifling, a cartridge receiving head reciprocatably mounted in said bore, lugs extending from said head into said grooves, and means 10 advancing said head to place a cartridge in said barrel and retracting said head to remove a cartridge from said barrel.
- 10 7. In a gun, a receiver, a breech block mounted and vertically slidable, in said receiver, said breech block having longitudinal guideways therethrough to receive a cartridge, and permit placing same in the barrel of said gun, an abutment at the forward end of said breech block below said guideways, means for shifting said breech block vertically, to align said guideways with said gun barrel and thereafter further shifting said breech block to position said abutment 15 behind said cartridge.
- 15 8. In a gun, a receiver, a breech block mounted, and vertically slidable, in said receiver, said breech block having longitudinal guideways therethrough to receive a cartridge, and permit placing same in the barrel of said gun, an abutment at the forward end of said breech block below said guideways, a cartridge engaging head reciprocatably mounted in said guideways, means for 20 shifting said breech block vertically to align said bore with said gun barrel, means for reciprocating said head to place a cartridge in the gun barrel, and thereafter further shifting said breech block to position said abutment 25 behind said cartridge.
- 25 9. In a gun, a breech block, vertically reciprocatable, said block comprising oppositely disposed longitudinal side members spaced apart, an abutment joining the forward end 30 of said members, said abutment having a centrally disposed opening therethrough for the passage of a firing pin, longitudinal grooves formed in said side members in alignment with said hole, a striker reciprocatably mounted in said grooves, and having a forwardly extending firing pin adapted to pass 35 through said hole, said striker comprising oppositely disposed longitudinal side bars connected at their front and rear ends by lateral bridges whereby a central opening is 40 left through said striker and breech block for the passage of cartridges, means for positioning said breech block to aline said striker with said gun barrel and means for actuating 45 said striker.

10. In a gun, a breech block, vertically reciprocatable, said block comprising oppositely disposed longitudinal side members spaced apart, longitudinal guideways formed in the upper portion of said side members, a cartridge engaging head reciprocatably mounted in said guideways, an abutment joining the forward end of said members, and disposed below said guideways, said abutment having a centrally disposed opening there-through for the passage of a firing pin, longitudinal grooves formed in said side members in alignment with said hole, a striker reciprocatably mounted in said grooves and having a forwardly extending firing pin adapted to 70 pass through said hole said striker comprising oppositely disposed longitudinal side bars connected at their front and rear ends by lateral bridges whereby a central opening is left through said striker and breech block for 75 the passage of cartridges, means for passing cartridges upward through said openings into engagement with said head, means for positioning said breech block to align said guideways with said gun barrel, and thereafter to 80 aline said striker with said gun barrel and means for actuating said striker.

11. In a gun, a receiver, a frame mounted therein, said frame having vertically disposed walls, a magazine disposed in said frame, vertical oppositely disposed ribs extending inward from the walls of said magazine and adapted to engage the extractor grooves of cartridges to be used therewith, a horizontally disposed and vertically reciprocatable floor plate mounted in said magazine, means for imparting vertical movement to said floor plate and means limiting the amount of said movement.

12. In a gun, walls, a magazine having 105 spaced side walls, vertical oppositely disposed ribs extending inward from said walls, and adapted to engage the extractor grooves of cartridges to be used therewith, a horizontally disposed and vertically reciprocatable floor 110 plate mounted in said magazine, and means for imparting a step by step vertical movement to said floor plate.

13. In a gun, a magazine having walls spaced apart, oppositely disposed ribs extending 115 inward from said walls, and adapted to engage the extractor grooves of cartridges, a floor plate movably disposed in said magazine, means for imparting a step by step movement to said floor plate, and means for 120 engaging said floor plate to prevent return movement thereof.

14. In a gun, a magazine having walls spaced apart, oppositely disposed ribs extending 125 inward from said walls, and adapted to engage the extractor grooves of cartridges, a floor plate movably disposed in said magazine, means for imparting a plurality of limited upward movements to said floor and means for engaging said floor to prevent re- 130

turn movement thereof, after each such movement.

15. In a gun, having a frame with oppositely disposed side walls, a pair of action bars longitudinally slidible therein, and means for actuating said bars, cartridge placing and removing means, comprising a pair of horizontally disposed guides, a cartridge engaging head reciprocatably mounted therein, a connecting link hinged thereto and extending rearwardly therefrom, a small link, a pin hinging said small link and connecting link and extending laterally therebeyond into guide slots formed in said frame, where-
15 by the rear end of said link is guided, a slotted link pivotally connected to said small link, a pivot pin hinging said slotted link to said frame, an action pin disposed in the slot in said link and extending laterally therefrom
20 through reversely curved slots in said frame, and into vertically disposed slots in said action bars.

16. In a gun, a breech block vertically reciprocatable, and means for retracting and raising same, said block having longitudinal guideways therein, a striker reciprocatably mounted in said guideways, said striker having longitudinally aligned flanges spaced apart and depending therefrom adjacent the rear end thereof, the front surface of the rear flange and the rear surface of the front flange inclining downwardly and forwardly along parallel paths, a cam block vertically reciprocatable below the rear end of said
30 striker, means for guiding said cam block, a double faced cam carried by said block and disposed between said flanges, a compression spring for urging said block upward, a sear for holding said block in retracted position
35 and a trigger for releasing said sear, whereby downward movement of said breech block will compress said spring and permit engagement of said sear with said cam block, and upward movement of said breech block
40 will position said striker in axial alignment with the gun barrel, and will separate said striker and cam block, retracting said striker into position to be snapped forward by upward motion of said cam block on release
45 by said sear.

17. In a gun, a striker longitudinally reciprocatable and vertically movable, said striker having longitudinally aligned flanges spaced apart and depending therefrom adjacent the rear end thereof, the front surface of the rear flange and the rear surface of the front flange inclining downwardly and forwardly along parallel paths, means for lowering and raising said striker, a cam block
55 vertically reciprocatable below the rear end of said striker, means for guiding said cam block, a double faced cam carried by said block and disposed between said flanges, a compression spring for urging said block up-
60 ward, a sear for holding said block in re-

tracted position, a trigger for releasing said sear, and means for depressing and raising said striker, said depression compressing said spring and permitting engagement of said sear with said cam block, and said raising
70 axially aligning said striker with the gun barrel, and moving said striker away from said cam block thereby retracting said striker into position to be snapped forwardly on release of said cam block.

In testimony whereof I hereunto affix my signature.

THOMAS E. FLOWERS.
